UNITED STATES PATENT OFFICE.

FREDERICK MAEULEN, OF RAHWAY, AND GEORGE L. VAN ALLEN, OF NEWARK, NEW JERSEY, ASSIGNEES TO BAKER & COMPANY, INC., A CORPORATION OF NEW JERSEY.

ANCHORAGE FOR ARTIFICIAL TEETH.

Application filed November 30, 1920. Serial No. 427,342.

To all whom it may concern:

Be it known that we, FREDERICK MAEULEN and GEORGE L. VAN ALLEN, citizens of the United States, and residents, respectively, of 5 Rahway, in the county of Union and State of New Jersey, and Newark, in the county of Essex and State of New Jersey, have invented new and useful Improvements in Anchorages for Artificial Teeth, of which 10 the following is a specification.

This invention relates in general to artificial teeth and more particularly to anchorages for securing the pins ordinarily employed in such teeth which are used for 15 fastening the teeth to bridges, backing, vulcanite, and the like.

The objects of the invention are to provide improved means for anchoring the pins in the body of the artificial tooth which is 20 simple and inexpensive and which will at the same time securely hold the pin in position; to provide an anchorage for such pins comprising a flanged cup member to receive the pin which provides a large soldering 25 area for soldering the pin to the cup thereby providing a strong and durable anchorage for the pin which will effectively withstand the strains to which such pins are subjected; to provide such an anchorage whereby the 30 pin can be easily applied to an artificial tooth with a minimum expenditure of time and labor; to provide a pin anchorage for artificial teeth consisting of a sheet metal cup having an integral exterior annular 35 flange formed of two thicknesses of the sheet metal of which the cup is formed; to provide an anchorage cup having an integral exterior flange formed by crimping the sides of the 40 cup inwardly into contact with the bottom thereof whereby the flange is reenforced, the soldering of the pin to the said cup securing the sides of the cup to the base to strengthen the same; and to obtain other results and 45 advantages as may be brought out by the following description.

Referring to the accompanying drawing, in which like numerals of reference indicate the same parts throughout the several views,

Figure 1 is an enlarged vertical sectional view through an artificial tooth showing a pin anchorage embodying our invention mounted therein;

Figure 2 is a longitudinal sectional view through the anchorage cup before the annular flange is formed thereon, and

Figure 3 is a perspective view of the anchorage cup embodying our invention.

In the embodiment of our invention illustrated in the drawings, the reference character 1 designates the cup anchorage for a conventional pin 2 which is used for the purpose of securing an artificial tooth 3 to a bridge, backing, vulcanite, or the like. The cup anchorage 1 is preferably formed of sheet metal and has an integral exterior 60 annular flange 4 at the base thereof, the said flange being formed in any suitable manner whereby portions of the sides of the cup are upset or crimped inwardly into contact with the bottom or base 5 thereof, the cup before 65 this crimping action taking place being substantially of the shape shown in Figure 2. It will thus be seen that the annular flange 4 comprises two thicknesses of the metal of which the cup is formed so as to be greatly 70 strengthened and reenforced.

The cup 1 is secured in the artificial tooth 3, which is formed of porcelain or the like, by any suitable process such as firing, the cup being embedded in the body of the tooth 80 and permanently baked therein. The interior diameter of the cup is slightly greater than the diameter of the shank of the pin 2 so that the pin will be snugly received within the cup.

The pin 2 may be secured in the cup in any of the known ways, as by dropping a piece of solder into the cup, then heating the facing sufficiently to melt the solder and forcing the pin into the cup against the 90 solder, the solder being distributed between the end and sides of the pin and the cup. It will thus be seen that an enlarged soldering area is provided within the cup 1, and the pin is securely held within the cup by being 95 soldered to both the base and the sides thereof. The solder 6 also reenforces the cup itself by connecting the sides of the cup with the bottom thereof at the inner edge of the annular flange 4 thus preventing the sides 100 of the cup from being pulled away from the bottom thereof when strain is exerted on the pin 2. When thus soldered the cup 1 and flange are substantially as solid as 105 would be the case were the cup and flange cast integrally with each other.

The flange 4 of the cup and also the outer end thereof provide an effective anchorage for the pin and positively prevent the cup from being pulled out of the tooth body 3, 110

and with our improved anchorage for the pin 2 it will be noted that the pin is effectively secured within the tooth body 3 so as to successfully withstand any strains to which such pins are ordinarily subjected.

Having thus described our invention, what we claim is:

1. A pin anchorage for artificial teeth comprising a metal cup having a portion of its side walls pressed inwardly into contact with the bottom of the cup to form an outwardly projecting flange exteriorly of the cup.

2. The combination with an artificial tooth and a pin to be secured therein, of a cup member secured in said tooth to receive said pin and having a portion of the side walls of the cup pressed inwardly into contact with the bottom of the cup to form an exterior annular flange on the cup comprising two thicknesses of the material of which said cup is formed, said flange positively holding the cup member within said tooth. 15
